(57) **CLAIM**

The ornamental design for a modularized electronic eyewear for personalized augmented reality audio, as shown and described.

DESCRIPTION

FIG. 1 is a front perspective view of an embodiment of an assembled modularized electronic eyewear for personalized augmented reality audio in the present invention having clear lenses or prescription lenses.

FIG. 2 is a front view thereof.

FIG. 3 is a rear view thereof.

FIG. 4 is a top view thereof.

FIG. 5 is a bottom view thereof.

FIG. 6 is a right side view thereof.

FIG. 7 is a left side view thereof.

FIG. 8 is a front perspective unassembled view thereof with the front frame portion and the side temple portions being spaced apart from each other and showing the connector features.

FIG. 9 is a front view thereof with the side temple portions being shown above the front frame portion for clarity.

FIG. 10 is a rear view thereof with the side temple portions being shown above the front frame portion for clarity.

FIG. 11 is a top view thereof.

FIG. 12 is a bottom view thereof.

FIG. 13 is a right side view thereof; and,

FIG. 14 is a left side view thereof.

The modularized electronic eyewear for personalized augmented reality audio in the present invention, has a modular front frame portion and modular side stem or temple portions that can be selectively chosen and removably assembled together with connector features. The front frame portion can be selected to have sunglass lenses, clear lenses or prescription lenses. The side temple portions can be selected to include desired selected features, audio speakers and associated electronics therein.
